US0D1022523S

(12) **United States Design Patent** (10) **Patent No.:** **US D1,022,523 S**
(45) **Date of Patent:** **** Apr. 16, 2024**

(54) **DISPENSING RECEPTACLE**

(71) Applicant: **simplehuman, LLC**, Torrance, CA (US)

(72) Inventors: **Frank Yang**, Rancho Palos Verdes, CA (US); **Joseph Sandor**, Newport Beach, CA (US); **Myk Wayne Lum**, Irvine, CA (US); **Adam C. Wade**, Rancho Santa Margarita, CA (US)

(73) Assignee: **simplehuman, LLC**, Torrance, CA (US)

(**) Term: **15 Years**

(21) Appl. No.: **29/877,099**

(22) Filed: **Jun. 1, 2023**

(51) LOC (14) Cl. **06-04**

(52) U.S. Cl. USPC **D6/521**

(57) **CLAIM**

The ornamental design for a dispensing receptacle, as shown and described.

DESCRIPTION

FIG. 1 is a perspective view, from above, of the front and left sides of a dispensing receptacle embodying a design hereunder;

FIG. 2 is a perspective view, from below, of the right side and rear thereof;

FIG. 3 is an elevational view thereof, from the front;

FIG. 4 is an elevational view thereof, from the rear;

FIG. 5 is an elevational view of the right side thereof;

FIG. 6 is an elevational view of the left side thereof;

FIG. 7 is a plan view of the top thereof; and,

FIG. 8 is a view of the bottom thereof.

The dot-dash-dot broken lines in the drawings indicate the boundaries of what is claimed and form no part of the claimed design. The dash-dash broken lines in the drawings depict aspects or portions that form no part of the claimed design.

1 Claim, 8 Drawing Sheets
